UNITED STATES PATENT OFFICE

171,681

DOLL

Laura P. Burleson, Fairview, N. C., assignor to
Sunset Products, Asheville, N. C., a partnership

Application December 29, 1952, Serial No. 22,911

Term of patent 7 years

(Cl. D34—4)

To all whom it may concern:

Be it known that I, Laura P. Burleson, a citizen of the United States, residing at Fairview, in the county of Buncombe and State of North Carolina, have invented a new, original, and ornamental Design for a Doll, of which the following is a specification, reference being had to the accompanying drawing, forming part thereof.

Figure 1 is a front perspective view of a doll, showing my new design, and

Figure 2 is a rear perspective view thereof.

I claim:

The ornamental design for a doll, as shown.

LAURA P. BURLESON.
